(57) **CLAIM**

The ornamental design for the toilet seat handle, as shown and described.

DESCRIPTION

The claimed toilet seat handle is used to attach to the underneath of a toilet seat.

FIG. 1 is a perspective view of the toilet seat handle showing my new design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines are included for the purpose of illustration and form no part of the claimed design.
